UNITED STATES PATENT OFFICE.

ALBERT B. DICK, OF LAKE FOREST, ILLINOIS, ASSIGNOR TO A. B. DICK COMPANY, OF CHICAGO, ILLINOIS, A CORPORATION OF ILLINOIS.

PRINTING APPARATUS.

1,031,630.

Specification of Letters Patent. Patented July 2, 1912.

Original application filed January 4, 1911, Serial No. 600,687. Divided and this application filed April 18, 1911. Serial No. 621,766.

To all whom it may concern:

Be it known that I, ALBERT B. DICK, a citizen of the United States, residing at Lake Forest, in the county of Lake and State of Illinois, have invented certain new and useful Improvements in Printing Apparatus, of which the following is a specification.

This invention relates to printing apparatus, and especially to printing machines for use in offices in printing multiple copies of letters and circulars in imitation of type-written work, for which use the apparatus would generally be operated by an unskilled person.

The object of the invention is to effect certain improvements in the construction of apparatus of this character, particularly with respect to the means for supporting the lines of type, to the end that superior results may be obtained, the amount of power required in operating the printing machine reduced, and the work of setting up the type and arranging them in the machine for printing facilitated.

The invention involves the use of a type-form in which each line of type may be assembled and supported as a unit, that is, independently of the other lines. To this end, each line of type in the form consists of a holder and type mounted thereon, this holder with the type thereon being type-high, so that it may be used in the same form with type of ordinary construction or with an electrotype. These holders are of a special construction, devised to secure low manufacturing cost thereof, to facilitate assemblage of the type thereon, and to properly hold the type during the printing operation.

I will first describe the construction of the devices which I prefer to employ and will then point out how these may be used and the advantages secured thereby, referring to the accompanying drawings, which show the preferred embodiment of the invention.

In these drawings, Figure 1 is a side elevation of one of the type-holders with type mounted thereon; Fig. 2 is a view similar to Fig. 1, broken away in part; Fig. 3 is a top view of the holder; Fig. 4 is a transverse section of the same; Fig. 5 is a view similar to Fig. 4, illustrating a slight modi-

fication; and Fig. 6 is a view illustrating certain portions of a printing mechanism and showing the manner in which the type-holders may be employed.

Referring to these drawings, the type-form consists of a plurality of lines of type, the type of each line being mounted upon a holder, so that each line of type may be set up and positioned in the form as a unit, independent of the other lines. Each holder with its type is type-high, so that when desirable the form may be made up in whole or in part of the line-units shown, as in some cases it may be desirable to have a portion of the form consist of type of the usual length or of one or more electrotypes. The holder for the line of type consists of two thin metallic plates 1 and 2, secured together side by side and having a dovetail groove 3 formed in the upper edge thereof, adapted to receive the lower ends of the type 4. The two strips 1 and 2 are similar and are of uniform cross-section from end to end, with the exception that one or both of the ends of the groove 3 are enlarged slightly, as shown at 5, to facilitate the entrance of the type into the groove. The formation of the holder from two similar strips in the manner indicated offers important advantages. A holder provided with a dovetail groove in the upper edge thereof may be constructed in this manner at much less cost than by making it from a single strip of metal, and furthermore the means for securing the two strips together may be such that after a line of type has been set up upon a holder the strips may be drawn together so as to grip the type rigidly between them. Whether the type be gripped rigidly or not, they will be supported in a definite vertical position with respect to the holder, by reason of the shoulders 6 on the type coacting with the upper edge of the holder, and when so supported their printing faces will be type-high.

In the accompanying drawings, I have shown screws 7 as a means for securing the pieces 1 and 2 together and for drawing them together to such extent as to cause them to grip the type in the groove 3. Furthermore, I provide means whereby, when the screws 7 are loosened slightly, the plates 1 and 2 will be forced apart, so as to release their grip upon the type. Certain of the

screws extending between the two plates 1 and 2 have springs 8 coiled thereon and lying in countersinks 9, these springs serving to spread the plates 1 and 2 when the 5 screws 7 are loosened.

Fig. 5 shows a slight modification of the construction above described, wherein the sides of the dovetail groove in the type-holder are inclined, so that when the plates 10 are drawn together the type will be drawn downwardly to cause their shoulders 6 to bear upon the upper face of the type-holder.

The construction herein shown for the type-holder is such that the operation of setting up and distributing the type is greatly 15 facilitated. A holder such as that herein shown may be mounted upon an automatic type-setting machine, the operation of which causes the type to pass one after another into 20 the upper end of the dovetail slot in the holder. After a line has been completely set up, a small block of rubber 10 may be made to slide into the end of the groove and against the end type of the line, to prevent 25 movement of the type lengthwise of the holder. The passage of the type into the groove is facilitated by the inclined sides of the groove at the end thereof, as shown at 5.

Fig. 6 shows the manner in which the 30 type-form is preferably used. 14 indicates the support for the type-form and 15 a sheet of rubber or other resilient material overlying the support. The type-form 16 is placed upon this pad 15, the several lines of 35 type being held in an upright position upon the pad but not tightly enough to preclude movement of one type-holder relatively to another. Ink is supplied to the printing 40 faces of the type by a ribbon 17, and the im- pressions are effected by a roller 18 adapted to rotate and to move bodily over the form of type and in coaction with the printing faces of the type through the impression-

sheet and ink-ribbon. With the lines of type arranged in line-holders as above described, each line may move relatively to the adjacent lines in the direction of the length of the type as the pressure-roller comes into coaction with the line, such movement being permitted by the resilient pad 15. For this 45 reason, a pressure-roller having a relatively hard surface may be employed and thus embossing of the impression-sheet avoided. Also, a lighter pressure of the roller upon the type will be sufficient to give the desired 50 results. Furthermore, by reason of the lighter pressure employed, the power necessary to drive the machine is decreased and less jarring of the parts of the machine takes place. 55

Having now described my invention, what I claim as new therein and desire to secure by Letters Patent is as follows:—

A form of type comprising a plurality of type-holders and a line of type supported 65 upon each type-holder, each type-holder with its type being type-high, and each type-holder consisting of two disconnected metallic strips of uniform cross-section throughout, lying side by side and having a 70 lengthwise dovetail groove in the upper edge thereof to receive the type, screws passing through said strips for drawing the strips together to grip the type, each screw having its head countersunk in one of the strips, and 75 springs interposed between the strips for separating the strips to release the type when such separation is permitted by said screws, substantially as set forth.

This specification signed and witnessed 80 this 14th day of April, 1911.

ALBERT B. DICK.
